(57) **CLAIM**

The ornamental design for a car rearview mirror, as shown and described.

DESCRIPTION

FIG. 1 is a front, top, right side perspective view of the car rearview mirror, showing our new design;

FIG. 2 is a rear, top, left side perspective view thereof;

FIG. 3 is a rear, top, right side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is a front view thereof in a state of use.

The broken lines illustrate portions of the car rearview mirror that form no part of the claimed design.

1 Claim, 10 Drawing Sheets
